US00D897415S

(12) **United States Design Patent** (10) **Patent No.:** **US D897,415 S**
(45) **Date of Patent:** **** Sep. 29, 2020**

(54) **CAMERA MOUNT**

- (71) Applicant: **GoPro, Inc.**, San Mateo, CA (US)
(72) Inventors: **John George Muhlenkamp, IV**,
Brisbane, CA (US); **Christopher Aaron**
Clearman, Half Moon Bay, CA (US)
(73) Assignee: **GoPro, Inc.**, San Mateo, CA (US)
(**) Term: **15 Years**
(21) Appl. No.: **29/675,551**
(22) Filed: **Jan. 3, 2019**

Related U.S. Application Data

- (63) Continuation of application No. 29/606,950, filed on Jun. 8, 2017, now Pat. No. Des. 841,721, which is a continuation-in-part of application No. 15/180,535, filed on Jun. 13, 2016, now Pat. No. 9,772,542, which is a continuation of application No. 14/883,431, filed on Oct. 14, 2015, now Pat. No. 9,395,031.

(57) **CLAIM**

The ornamental design for a camera mount, as shown and described.

DESCRIPTION

FIG. 1 is a bottom, front, left perspective view of a camera mount showing our new design.

FIG. 2 is a top, front, right perspective view of the camera mount shown in FIG. 1.

FIG. 3 is a bottom plan view of the camera mount shown in FIG. 1.

FIG. 4 is a front elevation view of the camera mount shown in FIG. 1.

FIG. 5 is a rear elevation view of the camera mount shown in FIG. 1.

FIG. 6 is a right elevation view of the camera mount shown in FIG. 1; and,

FIG. 7 is a left elevation view of the camera mount shown in FIG. 1.

The broken lines in the drawings illustrate unclaimed portions of the camera mount and form no part of the claimed design.

1 Claim, 3 Drawing Sheets
